United States Patent Office

Des. 214,803
Patented July 29, 1969

214,803

MODEL AIRPLANE

Alan V. Limb, 2250 Lake St., Salt Lake City,
Utah 84106

Filed Oct. 23, 1968, Ser. No. 14,146

Term of patent 14 years

Int. Cl. D21—02

U.S. Cl. D34—15

FIG. 1

FIG. 4

FIG. 1 is a top view of a model airplane showing my new design;

FIG. 2 is a bottom view thereof;

FIG. 3 is a front view of the airplane;

FIG. 4 is a rear view thereof; and

FIG. 5 is a side elevation view of the airplane.

I claim:

The ornamental design for a model airplane, as shown.
